UNITED STATES PATENT OFFICE

147,435

DESIGN FOR AN ICE CRUSHER

Elizabeth M. Dralle, New York, N. Y.

Application April 30, 1946, Serial No. 129,129

Term of patent 3½ years

(Cl. D89—1)

To all whom it may concern:

Be it known that I, Elizabeth M. Dralle, a citizen of the United States of America, and a resident of New York city, in the county of New York and State of New York, have invented a new, original, and ornamental Design for an Ice Crusher, of which the following is a specification, reference being had to the accompanying drawing, forming part thereof, in which—

Fig. 1 is a perspective view of an ice crusher embodying my design.

Fig. 2 is an end view thereof.

Fig. 3 is a top view thereof.

I claim:

The ornamental design for an ice crusher, as shown.

ELIZABETH M. DRALLE.
